UNITED STATES PATENT OFFICE.

JOHN HAMPSON, OF LONDON, ENGLAND, ASSIGNOR TO THIRD HAND PATENTS LIMITED, OF LONDON, ENGLAND.

INSECT-DESTROYING DEVICE.

1,032,208.

Specification of Letters Patent.

Patented July 9, 1912.

Application filed January 13, 1912. Serial No. 671,118.

To all whom it may concern:

Be it known that I, JOHN HAMPSON, a subject of the King of England, residing at 361 City road, London, England, have invented certain new and useful Improvements in Insect-Destroying Devices, of which the following is a specification.

This invention relates to devices for killing insects, such as wasps, flies and the like. 10 The device consists essentially of a pair of spring strips with their ends held normally in the open position by suitable means, but adapted to be allowed to spring together by the operation of a suitable part in order 15 to kill the wasp or other insect.

According to one way of carrying out the invention a strip of metal is provided to which a second somewhat similar springy strip is attached in such a way that the end 20 of the said springy strip is left free to turn up for a certain distance. To this free end is attached a wire link or the like, which is in turn attached to a sliding plate working upon the top of the strip. The strip is 25 formed at the other end into a shape resembling the handle of a pistol and a trigger is provided. The trigger is furnished with a projecting nose, preferably beveled, which takes into a slot and behind a catch provided 30 on the sliding piece, a suitable spring being furnished to keep the trigger pressed upward. And in order that my said invention may be better understood I will now proceed to describe the same with reference 35 to the drawing accompanying this specification in which:—

Figure 1 shows a side elevation of one form of the device; Fig. 2 shows plan of same; Fig. 3 shows perspective view; Figs. 40 4 and 5 show side elevation and plan respectively of a portion of a modified form of the device.

The same letters are employed to denote the same parts in all the views.

45 *a* shows a supporting portion consisting preferably of a strip of metal which is bent at *b* so as to form a handle or stock.

50 *c* is a striking portion consisting preferably of a strip of springy metal attached by rivets *d* to the strip *a*, in such a way that the end *e* is left free.

f is a slide which slides in a suitable guide *g*.

h is the bent up end of the slide *f*.

k is a slot cut in the guide piece *f* for the purpose hereinafter explained.

m is a trigger pivoted at *n* and provided with a spring *p*. The trigger *m* carries a nose *r* which is kept pressed upward by the spring *p*. The nose *r* is adapted when the slide *f* is pulled back to engage in the slot *k*.

s is a strip which is attached at one end to the slide *f* and at the other end to the back of the free end *e* of the strip *c*.

The ends of the strips *a* and *c* are made somewhat wider than the rest of the strips and provided with perforations *t* as shown on the drawing.

To set the device it is simply necessary to pull back the projection *h* against the springiness of the free end *e* of the strip *c* until the nose *r* springs up into the slot *k*. The position is then such as shown dotted at Fig. 1. When it is required to kill a wasp or the like it is simply necessary to so place the ends of the device that upon pulling the trigger *m*, the slide *f* is released which causes the free end *e* to spring downward thus killing the wasp between the end *e* and the strip *a*.

Referring to Figs. 4 and 5, in this case in place of depending upon the springiness of the metal a spring hinge *w* is provided, the rest of the device being the same.

In some cases the spring ends on one or both strips may be provided with padding.

Instead of providing a stock *b* and a trigger *m*, the springy closing device may be mounted upon a handle of other description, which may be of any length, and the operation of the closing spring may be effected by any suitable means such as a cord or the like releasing the catch, and other modifications may be made without departing from the principle of the invention.

It will be observed that with the form of the device shown in the drawing the setting and discharging may be effected with one hand, as it is simply necessary to bring the trigger finger above or below in order to actuate the trigger *m* or pull the slide *f* back by means of the turned up portion *h* as the case may be.

What I claim as my invention and desire to secure by Letters Patent of the United States of America is:—

1. An insect killer comprising a narrow extended portion having a handle and

- trigger at one end, a striking portion connected therewith by a flexible and resilient attachment so as to be capable of coming in contact with said extended portion when released, and means connected with said striking portion adapted to engage with said trigger when said striking portion is drawn back against the effort of said resilient attachment, substantially as described.
2. An insect killer comprising a supporting portion bent around to form a stock or handle, a trigger pivoted thereto and having a nose projecting up through said supporting portion, a striking portion connected to said supporting portion by a flexible and resilient attachment so as to be capable of coming in contact with said extended portion when released, and a slide connected with said striking portion adapted to engage with the nose of said trigger, substantially as described.
3. An insect killer comprising a supporting portion, a striking portion consisting of a strip of resilient metal fastened to the supporting portion and having a free end, a slide, a connection between the free end of
- said striking portion and said slide and a trigger carried by the supporting portion adapted to engage said slide, substantially as described.
4. An insect killer comprising an extended metal supporting portion bent around to form a stock or handle, a trigger pivoted thereto and having a nose projecting up through said supporting portion, a striking portion consisting of a strip of resilient metal fixed to said supporting portion at one end and having the other end free, a slide carried by said supporting portion and adapted to be engaged by the nose of said trigger, said slide having an upturned tip on its rear end, and means connecting the forward end of said slide with the free end of said striking portion, substantially as described.

In testimony whereof, I affix my signature, in presence of two witnesses.

JOHN HAMPSON.
